DESIGN FOR A MOUNTING FOR A PULLEY-CARRYING MOTOR

William D. Hamerstadt, Indianapolis, Ind., assignor to General Fibre Products, Incorporated, Indianapolis, Ind., a corporation of Indiana

Application September 9, 1935, Serial No. 58,480

Term of patent 14 years

To all whom it may concern:

Be it known that I, William D. Hamerstadt, a citizen of the United States and a resident of Indianapolis, in the county of Marion and the State of Indiana, have invented a new, original, and ornamental Design for a Mounting for a Pulley-Carrying Motor, of which the following is a specification, reference being had to the accompanying drawing, forming a part thereof.

In said drawing, Fig. 1 is a perspective view of a mounting for a pulley-carrying motor showing my new design; Fig. 2 is a top plan view of said mounting; and Fig. 3 is a front view of said mounting.

I claim:

The ornamental design for a mounting for a pulley-carrying motor, as shown.

WILLIAM D. HAMERSTADT.
